SILK SCREEN PRINTING PRESS

George W. Reinke, Park Ridge, Ill., assignor to
Roto-Screen Company, Chicago, Ill., a corpora-
tion of Illinois

Application November 3, 1950, Serial No. 193,904

9 Claims. (Cl. 101—126)

1

This invention relates in general to printing presses and, more particularly, to a new and improved silk screen printing press.

The method of printing, utilizing the silk screen process, is relatively old, having been performed by hand for many years. More recently, machines have been developed for carrying out the process, but for the most part they have been large, bulky devices expensive to manufacture and operate. Most silk screen printing machines have heretofore utilized the principle of a rotating drum or cylinder around which the stock to be printed upon is rolled during printing, while a silk screen is reciprocated in contact with the stock.

The hand method of utilizing the silk screen printing process avoided the use of expensive rollers and registering devices, but necessitated some means by which the screen could be withdrawn from the paper as the printing was being performed.

The principal object of the present invention is to provide a machine utilizing the silk screen method of printing wherein all of the advantages of both the hand method and machine method are combined into a simple and efficient mechanism.

Another object of the invention is to provide a silk screen printing press which, by means of simple adjustments, may be utilized for printing on flexible material such as paper or cardboard, as well as on rigid material such as glass and sheet metal.

A further object of the invention is to embody in a single machine a novel arrangement of mechanism, whereby the various operations necessary for performing silk screen printing are all carried out in a predetermined sequence and timed relationship.

Still another object of the invention is the provision of a so-called flange or hold-down bar which is caused to move in a predetermined path during operation of the machine for gripping the edge of flexible material, such as paper, during the printing operation, but which may be adjusted to become ineffective for gripping purposes when rigid stock is used.

A still further object of the invention is to provide a novel arrangement for the squeegee member which operates to force ink through the open interstices of the silk screen during the printing operation.

Another object of the invention is to provide a flexible frame for the silk screen, together with novel means operable to flex the screen progressively away from the stock being printed upon

2

during the printing operation so that, at the completion thereof, the screen will be completely free of the stock and may be removed to allow the next succeeding sheet to be inserted in its place.

5 A further object of the invention is to provide a novel arrangement in a silk screen printing press, whereby the stock printed upon will be allowed to leave the machine by gravity, thereby permitting the next succeeding sheet to be fed into the machine.

10 A further and more specific object of the invention is to provide a novel arrangement for the inking fountain on the frame of the silk screen, together with a wipe-off bar at the opposite end 15 of the screen, whereby the squeegee may cooperate with these two members to apply the right amount of ink through the screen and yet prevent any excess of ink from dropping back onto the screen after the printing operation has been completed.

15 Other objects and advantages of the invention will become apparent upon reading the following description taken in conjunction with the accompanying drawings in which:

20 Fig. 1 is a rear elevational view of a machine embodying the present invention;

25 Fig. 2 is a vertical sectional view through the machine taken along line 2—2 of Fig. 1;

30 Fig. 3 is a fragmentary perspective view taken substantially along the plane of line 3—3 in Fig. 1 and illustrating the relative positions of all of the cams on the main cam shaft at the time a sheet is being placed in the machine prior to printing thereon;

35 Fig. 4 is a fragmentary vertical sectional view along the line 4—4 of Fig. 3 illustrating the relative positions of the squeegee, screen, and two of the cams;

40 Fig. 5 is a fragmentary vertical sectional view along line 5—5 of Fig. 3 illustrating in elevation the position of the cam for operating the side guide;

45 Fig. 6 is a fragmentary vertical sectional view along line 6—6 of Fig. 3 showing in elevation the cam for operating the flange bar;

50 Fig. 7 is a fragmentary perspective view similar to Fig. 3, but showing the relative positions of the various cams at the beginning of the printing operation;

55 Fig. 8 is a fragmentary vertical sectional view along line 8—8 of Fig. 7 and similar to Fig. 4 showing the positions of the squeegee, the screen, the cams for operating the front guide fingers and for elevating the screen at the beginning of the printing operation;

Fig. 9 is a fragmentary vertical sectional view

along line 9—9 of Fig. 7 and similar to Fig. 5, but showing the side guide cam in its position at the beginning of the printing operation;

Fig. 10 is a fragmentary vertical sectional view along line 10—10 of Fig. 7 and similar to Fig. 6, but showing the flange bar cam in its position at the beginning of the printing operation;

Fig. 11 is a fragmentary perspective view similar to Figs. 3 and 7, but showing the cams on the same shaft in their respective positions near the completion of the printing operation;

Fig. 12 is a fragmentary vertical sectional view taken along line 12—12 of Fig. 11 and similar to Figs. 4 and 8, but showing certain of the screen and front guide finger cams in their position near the completion of the printing operation;

Fig. 13 is a fragmentary vertical sectional view taken along line 13—13 of Fig. 11 and similar to Figs. 5 and 9 illustrating the position of the side guide cam near the completion of the printing operation;

Fig. 14 is a fragmentary vertical sectional view taken along line 14—14 of Fig. 11 and similar to Figs. 6 and 10, but showing the flange bar cam in its position near the completion of the printing operation;

Fig. 15 is a fragmentary perspective view similar to Fig. 11, but showing the positions of the cams immediately after completion of the printing operation;

Fig. 16 is a fragmentary vertical sectional view taken along line 16—16 of Fig. 15 and showing the various parts of Fig. 12, including the screen and front guide finger cams in their positions immediately after the completion of the printing operation;

Fig. 17 is a fragmentary vertical sectional view taken along line 17—17 of Fig. 15 and similar to Fig. 13, but showing the side guide cam in its position immediately after completion of the printing operation;

Fig. 18 is a fragmentary vertically sectional view taken along line 18—18 of Fig. 15 and similar to Fig. 14, but showing the flange bar cam in its position immediately after completion of the printing operation;

Fig. 19 is an enlarged fragmentary vertical sectional view illustrating the position of the end gauge fingers and the flange or hold-down bar at the time when the stock is fed into the machine;

Fig. 20 is a view similar to Fig. 19 showing the various parts in their position at the beginning of the printing operation;

Fig. 21 is similar to Fig. 20 and illustrates the parts in their positions near the end of the printing operation;

Fig. 22 is a view similar to Figs. 19, 20 and 21, but showing the positions of the parts after the printing operation has been completed, wherein the printed stock is allowed to be delivered from the machine;

Fig. 23 is an enlarged fragmentary sectional view through the end gauge fingers and flange or hold-down bar illustrating the parts in their positions when adjusted for rigid stock such as glass or metal;

Fig. 24 is an enlarged fragmentary sectional view taken along the line 23—23 of Fig. 16;

Fig. 25 is an enlarged fragmentary vertical sectional view through the squeegee and illustrating the mounting thereof onto its chain drive; and

Fig. 26 is a fragmentary perspective of the squeegee assembly at one end thereof.

Referring now more particularly to the drawings and especially to Figs. 1 and 2, the machine comprises a suitable frame structure adapted to support the various moving parts thereof, which frame structure includes vertical side members 1 and 2 at the rear of the machine and similar vertical side members 3 at the front of the machine. A suitable form of base 4 may be rigidly secured between the rear side members 1 and 2, and one or more additional side members 5 may be provided intermediate the front and back of the machine.

A reinforcing angle member 6 is preferably horizontally disposed at each side of the framework and may extend from the front to the rear of the machine. Other reinforcing angle members may be provided such as the member 7 extending across the rear of the machine and the members 8 horizontally disposed at each side of the frame. Other horizontal reinforcing angle members 9 may also be provided as illustrated, all of which may be suitably secured together to form a rigid framework.

Within the framework of the machine there may be a supporting member 10 in the form of a T extending horizontally between the sides of the frame for supporting a bearing mounting 11 intermediate the ends thereof. A bearing 12 is mounted on the supporting member 11 in which a horizontally disposed shaft 13 is journaled for rotation. The ends of shaft 13 may be rotatably mounted in suitable bearings at each side of the framework.

Shaft 13 is the main cam shaft and has mounted thereon four cams adjacent each end thereof. These cams are so shaped and positioned on the shaft relative to each other as to each operate a different part of the press in synchronized timed relation during the operation thereof. These four cams, which have identical corresponding cams at the opposite end of shaft 13, are indicated by the numerals 14, 15, 16 and 17 and may be seen in rear elevation in Fig. 1 and in perspective in Figs. 3, 7, 11 and 15.

A second cam shaft 18 is located above and rearwardly of shaft 13 and is mounted for rotation in suitable bearings at each side of the machine. Cam shaft 18 is provided with two identical cams 19, one adjacent each end thereof. Cams 19 operate to raise and lower the bed frame on which the stock is positioned for printing and are actuated in timed relation with the cams on shaft 13. A sprocket wheel 20 is secured on shaft 13 at one end thereof, and a similar sprocket wheel 21 is mounted on one end of shaft 18. Suitable connecting means between these sprockets and a power source causes the two shafts to rotate simultaneously at the same rate of speed.

The driving mechanism.

The power for driving the cam shafts and causing operation of the machine is provided by a suitable source such as an electric motor 22 provided with a pulley 23 on the shaft 24 (Fig. 1). A belt 25 is trained over the motor pulley 23 and over a pulley 26 mounted on shaft 27 of a speed reducer 28. A shaft 29 extends from the speed reducer 28 and has a sprocket wheel 30 mounted on one end thereof. A chain 31 is trained around sprocket wheel 30 as well as sprocket wheel 20 on shaft 13 and sprocket wheel 21 on shaft 18. Any slack in the chain is taken up by an idler sprocket wheel 32 suitably mounted for adjustment at one side of the frame.

Another sprocket wheel 33 is mounted on the

opposite end of shaft 29. A chain 34 is trained around sprocket wheel 33 and another sprocket wheel 35 mounted on shaft 36 which shaft extends between the sides of the framework. A plurality of pulleys 37 are mounted in spaced relation along the length of shaft 36. Each pulley 37 has a belt 38 trained therearound and around a corresponding pulley 39 on shaft 40. This shaft 40 is suitably mounted for rotation in bearing members 41 located on the outer ends of upwardly and outwardly extending supporting arms 42 at each side of the machine. Rotation of shaft 29 from the speed reducer will thus drive the pulleys 37 and the various belts 38 for the purpose of removing the printed stock from the press after the printing operation, as will be pointed out more specifically hereinafter. The printed stock is allowed to leave the bed frame by gravity after the printing operation has been completed, whereupon it is delivered to the moving belts 38 where an operator may remove the printed stock from the machine.

The bed plate

A bed frame is provided to which the stock is fed and which supports the stock during the printing operation. This bed frame generally indicated at 43 in the various figures of the drawings, consists of spaced side arms 44-45. These side arms are preferably secured together by one or more cross members 46 to maintain the bed frame rigid. A plurality of supporting plates 47-48-49 may be fixed to the cross member 46 in spaced apart relation so that a bed 50 may be rigidly secured thereto.

The side arms 44 and 45, together with the bed plate 50, comprising the bed frame 43, are mounted for rocking movement on shaft 13. As will presently appear, the screen is mounted above the bed plate 50 and suitable means are provided to rock the bed frame from the open position of Fig. 4, at which time the stock may be fed thereto, to the closed position of Fig. 8 against the underside of the screen. This rocking movement of the bed frame is accomplished by rotation of cams 19 mounted on each end of shaft 18. Each of the side arms 44-45 has a cam follower 50a mounted thereon in rolling contact with the edge of cam 19. Thus, it will be evident that as cam 19 rotates in a counterclockwise direction from its position of Fig. 4 to its position of Fig. 8, the side arms 44 and 45 will be rotated in a counterclockwise direction about the shaft 13 as a center.

The front gauge

One of the novel features of the present invention includes a front gauge or guide means for the stock so that each sheet will be fed into the machine to the same position for every printing operation. In the present machine the front gauge fingers are caused to be elevated a short distance above the bed plate at the time the stock is fed into the machine. These fingers are then lowered a short distance during the printing operation, and are then lowered still farther after the printing is completed, so that the printed stock may fall by gravity over the front gauge to be carried away by the belts 38.

A shaft 51 extends between the lower ends of the side arms 44 and 45 and has mounted thereon in spaced relationship a plurality of arms 52. These arms are secured together intermediate their ends by means of a cross bar 53. While Fig. 1 shows that there are four such arms 52, it will be evident that any suitable number desired may be utilized.

These arms 52 extend rearwardly and upwardly from shaft 51 and each is provided at its upper end with a gauge or guide finger 54 mounted thereon by any suitable means such as screws 55. 5 These gauge fingers are illustrated in section in Figs. 19 to 22, and 25, and are shown in relation to the bed plate 50 in Figs. 3, 7, 11 and 15. All of the arms 52 together with their respective gauge fingers 54 are raised and lowered at properly timed and synchronized intervals by means of the cams 14 adjacent each end of shaft 13. The outermost of the bars 52 each has a cam follower 56 which is maintained in contact with the edge of its associated cam 14 by gravity. The cams 14 are so shaped that during the rotation thereof the arms 52 will be elevated above the bed plate 50 at the time the stock is fed into the machine. The forward edge of the stock will then come against the gauge fingers 54 which regulate the position of the stock with respect to the screen. Each cam 19 rotates to elevate the bed plate 50 against the underside of the screen after the stock is in proper register. The arms 52 will then drop downwardly a short distance as will presently be described.

The flange bar

Inasmuch as the machine of the present invention has universal application and is designed to accommodate any kind of stock, including thin paper, flexible cardboard and heavier rigid material, such as glass and sheet metal, mechanism is provided which is useful in connection with certain material, but unnecessary when other material is used. For example, one common way of preventing movement of thin paper on a bed plate is by means of a vacuum. Thus, a vacuum may be created to hold the paper in place during the printing operation and then released after the printing has been completed. Such a vacuum bed may be used in connection with the present machine although the details thereof have not been shown since it is a well-known expedient.

When other stock, such as cardboard, is used, then it may be desirable to provide some gripping or clamping means to grip the edge of the stock and hold it in place during printing. When other material, such as glass or sheet metal, is printed upon, it is unnecessary to provide any additional holding means therefor, it being sufficient to allow the sheet to rest at its forward edge against the gauge fingers during printing, although additional means, such as a vacuum bed, could be used if desired.

In the present case a flange bar or hold-down bar 57 is mounted transversely of the arms 52 adjacent the upper ends thereof and may be brought into position for the purpose of clamping stock to the bed plate during printing. This flange bar 57 is provided with a plurality of elongated openings 58 each in alignment with one of the bars 52. The lower inner part of each slot 58 is made smaller as at 59 thereby providing a shoulder or ledge 60 between the upper and lower faces of the flange bar 57 (Figs. 19 to 22). The upper part of each slot 58 is of a size to receive the heads 61 of a pair of bolts 62, the undersides of the heads 61 being adapted to bear against the shoulder 60. The bolts 62 extend downwardly through the associated bar 52 and thus secure the flange bar 57 to the bars 52.

The flange bar 57 will thereupon be raised and lowered with the bars 52. The slots 58 in the flange bar cooperate with the bolts 62 to permit

also a sliding movement of flange bar 57 in a direction toward and away from the bed plate 50. Thus, Fig. 19 illustrates the flange bar 57 in an intermediate position. Figs. 20 and 21 show the flange bar 57 in its extreme position toward the bed plate 50, while Fig. 22 illustrates the flange bar in its extreme position away from the bed plate 50. This forward and backward movement of the flange bar 57 is accomplished by means of the cams 15 mounted at each end of shaft 13. Each end of the flange bar 57 has secured to the underside thereof a bar 63 fixed by means of bolts 64. An arm 65 extends angularly downwardly from each bar 63 and has a cam follower 66 rotatably mounted thereon. Each cam follower 66 is adapted to contact the edge of a cam 15 at opposite sides of the machine, which thereupon move the flange bar 57 with respect to the bars 52. This movement and the manner in which it is accomplished may be more readily understood by viewing Figs. 6, 10, 14 and 18. In these figures cam 15 is shown in progressively different positions corresponding to the positions of the flange bar 57 shown in Figs. 19, 20, 21 and 22.

The forward longitudinal edge of the flange bar 57 is provided with an undercut portion 67 adapted to clampingly contact the forward edge of a sheet of stock which has been fed into the machine against the guide fingers 54. In the various figures the numeral 68 represents a sheet of stock fed into the machine until the forward edge thereof contacts the guide fingers 54. The position of the various parts will be like that shown in Figs. 3, 4, and 19. When the flange bar is used, the cam 15 will cause the flange bar to move toward the bed plate 50 to the position shown in Figs. 10 and 20, while at the same time cam 14 has permitted the bars 52 carrying the flange bar 57 to drop downwardly to a position where the forward edge of the flange bar contacts and holds the edge of the stock in the machine. As the machine continues with its cycle, and during the printing, the bars 52 and flange bar 57 will remain in the position shown in Figs. 20 and 21. When the printing has been completed, suitable means, such as the spring 69, will draw the flange bar 57 away from the bed plate when it is permitted to do so by cam 15, whereupon cam 14 will allow the bars 52 and flange bar 57 to drop downwardly below the forward edge of bed plate 50 to the position shown in Figs. 15, 16 and 22. The stock will then be free to slide downwardly by gravity to the belts 38.

The foregoing describes briefly the operation of the front guide fingers and the flange bar when stock of particular material, such as paper or cardboard, is used and which must be held against the bed plate at its forward edge. As stated hereinabove, it is not necessary to use the flange bar when certain other materials, such as thin paper, glass or metal, is the stock printed upon. In all cases the stock is fed into the machine until the forward edge thereof comes against the gauge fingers. With certain materials no additional holding means is necessary to hold them against inadvertent shifting movement during printing or after registering. In other cases a vacuum bed may be provided. In any event, the machine embodying the present invention is capable of being used with any of these materials.

Considering Fig. 23, the adjustment is there shown, whereby the flange bar may be moved

to a position where it will not be caused to move toward and away from the bed plate or at least will not be caused to so move a sufficient distance to be effective as a clamping means.

When this adjustment is to be made, the bolts 64 may be loosened and the bar 63 and arm 65 carrying the cam follower 66 at each side of the machine may be moved a short distance in the direction of the bed plate so that the cam follower 66 will be moved either entirely out of the path of cam 15 or substantially so, thereby preventing any substantial movement of the flange bar toward and away from the bed plate. When the flange bar 57 is thus adjusted, it will still move up and down with the arms 52 by means of the cams 14, but will not have sufficient forward movement to overlap the work.

If desired, any suitable means such as a pin (not shown) may be positioned at a suitable place on the machine frame to maintain the arms 52 and gauge fingers 54 a sufficient distance above the bed plate 50 to retain the stock thereon during the printing operation. At the completion of the printing these parts may then be allowed to drop downwardly, as previously described, to permit the stock to fall by gravity to the belts 38.

The side guide

In printing operations the stock must be registered not only at its forward edge, but also along one side thereof to insure that the stock lies squarely on the bed plate with respect to the screen. In the present instance, the side guide or gauge pin mechanism and the operation thereof are clearly illustrated in perspective in Figs. 3, 7, 11 and 15. Their corresponding sectional views are particularly shown in Figs. 5, 9, 13 and 17.

Referring particularly to these figures, it will be noted that the bed plate 50 is provided adjacent the forward edge thereof, and preferably at each side, with several openings such as those shown at 70 and 71. A transversely extending bar 72 is located below the bed plate 50 and immediately beneath the various openings 70 and 71. A forwardly extending arm 73 is mounted on each end of the bar 72 and has pivotal movement on the side frame members 44 and 45 as at 74. Thus, the transverse bar 72 may be raised and lowered in accordance with a rocking motion imparted to the arms 73.

A pin or cam follower 75 is positioned adjacent the forward end of each arm 73 and is adapted to contact the edge of the adjacent cam 16 on the lower side thereof. The arrangement of arms 73, bar 72, and pivots 74 is such that the weight behind pivot pins 74 will have a tendency to rotate arms 73 in a clockwise direction and urge the pins 75 upwardly against the edge of cams 16. These cams 16 are so shaped as to cause the arms 73 to rock causing the transverse bar 72 to be raised and lowered at predetermined timed intervals during the cycling of the press.

The transverse bar 72 is provided with a plurality of upwardly extending pins 76 each positioned immediately below one of the openings 70 and 71. A side guide member or gauge finger 77 is adapted to be placed over any one of the pins 76 and is of such length that it will extend through the adjacent opening 70 or 71 and above the upper surface of bed plate 50 when the bar 72 is in elevated position as shown, for example, in Figs. 3, 4 and 5.

When stock is inserted in the press, the for-

ward edge thereof may come against the front guide fingers 54, and one side thereof is caused to contact the side guide 71. When the stock is thus in register and the bed plate is elevated to come against the underside of the screen, the cams 16 will have rotated to their positions shown in Figs. 7 and 9 thereby allowing the bar 72 to move downwardly a sufficient distance to bring the side guide 71 below the upper surface of bed plate 50. Thus, the side guide does not create any interference with the screen or screen frame as the squeegee is moved thereover. After the printing operation has been completed, the cams 16 will have rotated to the position of Figs. 15 and 17 to elevate the side guides 71 a sufficient distance again to be in registering position for the next sheet of material.

The screen and screen frame

At each side of the machine additional strengthening members in the form of elongated plates or bars 78 are rigidly secured between the intermediate uprights 5 and the rear uprights 1 and 2. A cross member 79 extends between these plates 78 at the upper rear end thereof as may be seen clearly in Figs. 1, 2, 4, 8, 12 and 16. An additional cross member 80 is welded or otherwise fixed to member 79 and has mounted thereon a plurality of spaced L-shaped clamping members 81. As is customary, the silk screen is secured in a frame, but the frame in this instance, generally indicated by the numeral 82, has certain novel features of construction which will now be described. The screen frame 82 has a cross member 83 at its upper end preferably consisting of a wooden member 84 and a thin metal plate 85 mounted on one side thereof. The side members of the frame also consist of a bottom wooden member 86 and a top metal member 87 fixed thereto. This construction, including the combination of a thin metal strip and a wood strip, provides for strength in the frame as well as permitting a certain amount of resiliency so that it may be easily bent or flexed during the printing operation to lift the screen away from the stock progressively as the ink is being applied thereto.

The bottom of the frame has a cross member 88, and a trough 89 is located between the frame sides at the bottom thereof and is adapted to hold a quantity of ink.

The entire screen frame is held against lateral movement by clamping in the machine framework. The upper end 83 of the screen frame consisting of the cross members 84 and 85 is placed against one side of the L-shaped members 81 and are then held in that position against movement by a clamping or wipe-off bar 90. A plurality of bolts 91 corresponding in number to the L-shaped members 81 each extends through a lug 92 extending forwardly from the cross member 79. The bottom ends of bolts 91 thereupon contact the upper face of clamping bar 90, thereby clamping the upper end of the screen frame 82 rigidly in place.

The cams 17 at each end of shaft 13 are the operating cams for elevating the lower end of the screen during the printing operation. In order to accomplish this, there is provided a bar 93 (Figs. 3, 7, 11, 12, 15, 16 and 22) at each side of the machine pivotally mounted on the shaft 51. The upper or rear end of each bar 93 has a pin 94 extending inwardly therefrom. The pin 94 at each side of the machine is of sufficient length to accommodate a cam follower 95 and a

roller 96. The cam follower 95 engages the edge of its associated cam 17, whereby rotation of the cam will raise and lower arm 93. Roller 96 is adapted to contact the underside of the side members 86 of the screen frame so that as the bar 93 is raised and lowered the lower end of the screen frame will likewise be moved upwardly and downwardly.

The cams 17 are so positioned on shaft 13 with respect to the other cams heretofore described that rotation thereof during the machine cycle will cause the bottom portion of the screen to begin an upward movement immediately behind the squeegee as the printing operation is being carried out. As soon as the printing operation has been completed and the printed stock has left the bed frame, the cams 17 will permit the screen to assume its normal flat position as the bed plate is being lowered to receive the next succeeding sheet of material.

The squeegee assembly

A stub shaft 97 (Fig. 2) is mounted at one side of the machine and has two sprocket wheels mounted for rotation thereon. One such sprocket wheel may be seen in Fig. 2 and is indicated at 98. Another sprocket wheel 99 is mounted for rotation on a stub shaft 100 at each side of the machine at the upper part of the plates 78. Referring for a moment to Fig. 2, it will be noted that a chain 101 is trained around sprocket wheels on shaft 36 and shaft 97. Chain 102 at each side of the machine is trained around the sprocket wheels 98 and 99. When motor 22 drives shaft 29 from speed reducer 28 to rotate shaft 36, as heretofore explained, chain 101 will drive chain 102 by means of the respective sprocket wheels around which these chains are trained.

The squeegee assembly is generally indicated by the numeral 103 in Figs. 4, 8, 12 and 16, and the details of this assembly may be understood more clearly by viewing Figs. 25 and 26. This squeegee assembly 103 is mounted for movement 45 with chain 102 and is maintained in proper position during the printing operation by the aid of a bar 104 at each side of the machine extending between the respective sprocket wheels 98 and 99.

The squeegee assembly is composed of an upper plate 105 which has a pair of spaced bars 106 and 107 rigidly attached thereto and extending downwardly therefrom. A spacer or backing bar 108 is located between the bars 106 and 107 and is adapted to back up the edge of the squeegee blade 109. This blade 109 is formed of a flexible material such as rubber, or the like, and is clamped between the bars 106 and 107 by means such as screws. The outer edge of blade 109 will extend a sufficient distance beyond bars 106 and 107 so as to flex slightly and yet be sufficiently firm when in contact with the silk screen to force the ink through the screen onto the stock.

This squeegee assembly 103 extends between the chains 102 at each side of the machine and is provided with a novel mounting means whereby the assembly may be carried with the chains as they are driven during the cycle of the machine.

A hub member 111 at each side of the machine is adapted to have the ends of plate 105 secured thereto by means such as bolts 112. Each hub 111 also has mounted thereon a pair of spaced rollers 113 and 114 between which is located a substantially triangular plate member 115. A connecting bar 116 is fastened at its ends to the plates

115 to increase the rigidity of the entire assembly and to cause the assembly to be maintained in proper alignment at all times.

The narrow end of each plate 115 is provided with a pin 117 on which a roller 118 is rotatably mounted. The outer end of each hub member 111 is secured rigidly to the associated chain 102 by fixing one of the links of the chain to the end of the hub to prevent any relative rotation thereof. This mounting may be accomplished in any suitable manner but in actual practice it has been found expedient to remove adjacent pins from one of the chain links and substitute therefor longer pins having a press fit into suitable openings on opposite sides of the center of the hub.

The outer roller 114 at each side of the machine and the smaller rollers 118 cooperate to maintain the squeegee blade 109 against the screen during the printing operation by contacting the lower edge of bar 104. The inner roller 113 is caused to bear downwardly and roll against the side members of the screen frame, thereby preventing cam 17 from elevating the screen away from the stock at any point except rearwardly of the squeegee during printing, and insures that the screen will be maintained against the stock at all points forwardly thereof.

A quantity of ink 119 is initially placed in the trough 89 so that the squeegee blade may pick up some of this ink and spread it over the screen during printing. At the end of the printing operation there will still be a quantity of ink which the blade will carry with it to the top of the screen and which will be left at that point as the blade leaves the screen. Such quantity of ink at the top of the screen is indicated by the numeral 120. In order to prevent any excess ink from running back onto the blade and dropping back onto the screen, the lowermost edge of wipe-off bar 90 is so positioned as to act as a wipe-off member against which the forward edge of the squeegee blade may come as it is caused to move upwardly away from the screen, as illustrated more clearly in Fig. 16.

After the first printing operation has occurred, the quantity of ink 120 at the top of the screen actually acts as the inking fountain. The reason for this is that after the ink has been deposited there the squeegee assembly then travels downwardly along the upper reach of chains 102 to begin the next printing operation. The squeegee blade will have retained some of the ink thereon in a sufficient quantity for the next printing operation. When it reaches the top of the screen the ink at that point will have started to flow downwardly, but the squeegee blade will pick up a quantity of this ink and retain it during the movement downwardly and back to initial printing position. The wipe-off bar 90 merely wipes the edge of the squeegee blade so that excess ink will not drop back onto the screen.

Operation

In the operation of the machine, the various parts heretofore described will be in their positions shown in Figs. 3 to 6, inclusive. The side arms 44 and 45 carrying the bed plate 50 will be in their lowermost position so that the cam roller 50a thereon is in contact with the lowest part of cam 19. The arms 52 carrying the front guide fingers 54 will be in elevated position where the cam rollers 56 are in contact with the highest part of cams 14. The arms 73 carrying bar 72 on which the side guide 77 is mounted will have the cam pins 75 thereof in contact with the highest

part of cams 16 so that the guides 77 will be elevated above the surface of the bed plate 50. The parts are thus in position to receive a sheet of stock 68 on the bed plate 50 and to register properly the stock at the forward edge thereof and along one side. At this point the squeegee assembly 103 has almost reached the lower end of chain 102 prior to the beginning of the printing operation.

10 As the machine begins its cycle, cams 19 rotate to elevate the bed plate 50 with the stock 68 thereon up to a position into contact with the screen, as shown in Fig. 8. At this point cam 14 will have rotated a sufficient distance so that the 15 cam roller 56 will be in contact with the lowest point on the cam 14 to lower the bars 52, guide fingers 54 and flange bar 57 to clamping position for clamping the forward edge of the stock, if the stock is of such nature that the flange bar is 20 needed. Cam 16 will have rotated to a position shown in Fig. 9 where pin 75 is in contact with the lowest point on the cam whereupon the side guide 77 will be lowered beneath the surface of bed plate 50 and prevent any interference with 25 the screen. At this point the squeegee assembly 103 will have started its upward travel with the lower reach of chain 102 and is ready to begin the printing operation.

As the printing continues cam 17 is being rotated to elevate arms 93 which have their rollers 96 in contact with the underside of the screen. The lower end of the screen is thus elevated progressively as the squeegee moves upwardly across the screen. The rollers 113 at each side 35 of the machine, being in contact with the upper surface of the screen, will prevent the screen from being lifted from the stock at all points forwardly thereof. Fig. 12 illustrates these various parts near the completion of the printing operation.

30 When the printing is completed and the machine continues the cycle, the squeegee assembly 103 will continue its upward movement to pick up more ink to carry back to the initial printing position thereof. After this ink has been picked up by the squeegee the front edge of the blade 40 will be wiped off by the edge of bar 90.

When the printing operation has been completed, cams 14 will allow the flange bar 57 and guide fingers 54 to drop downwardly below the bed plate 50 whereupon the printed stock 68 will fall by gravity to the belts 38 for conveyance away from the machine. Cam 19 will have rotated to the position shown in Fig. 16 where cam follower 50a begins to move toward the lowest 50 point on the cam to return the bed plate 50 back to its original position. Cam 16 acts on pin 75 to elevate the side guide 77 back to its position above the bed plate 50, and cam 17 allows the screen to be returned to its initial position to 55 begin the next printing operation.

60 From the foregoing description, it will be observed that many novel features have been brought together and combined in a unitary machine which is capable of universal adaptation. That is to say, with the present invention it has 65 become unnecessary to manufacture a different machine for each different material to be printed upon. All machines may be constructed in the same way and only minor adjustments are required to permit printing on thin paper, heavy paper, cardboard or rigid materials, such as glass or sheet metal.

Changes may be made in the form, construction and arrangement of parts from those disclosed herein without in any way departing from 70

the spirit of the invention or sacrificing any of the attendant advantages thereof, provided, however, that such changes fall within the scope of the claims appended hereto.

The invention is hereby claimed as follows:

1. A silk screen printing press comprising a main frame, a bed adapted to receive a sheet of material to be printed upon, a screen positioned above said bed, means for imparting a relative movement between said bed and screen toward and away from each other for printing, a squeegee for forcing ink through said screen, means for moving said squeegee from one end of said screen to the other end thereof and return, and cam means operable in timed relation with the movement of said squeegee for flexing said screen progressively away from said bed immediately behind said squeegee during printing.

2. A silk screen printing press comprising a main frame, a bed mounted for rocking movement on said frame and adapted to receive a sheet of material to be printed upon, a screen positioned above said bed, means for rocking said bed toward and away from said screen for printing, a squeegee for forcing ink through said screen, means for moving said squeegee from one end of said screen to the other end thereof and return, and cam means operable in timed relation with the movement of said squeegee for flexing said screen progressively away from said bed behind said squeegee during printing.

3. A silk screen printing press comprising a main frame, an angularly disposed bed mounted for rocking movement on said frame and adapted to receive a sheet of material to be printed upon, a screen positioned above said bed, means for rocking said bed toward and away from said screen for printing, a squeegee for forcing ink through said screen, means for moving said squeegee from one end of said screen to the other end thereof and return, front end guide means and side guide means for properly registering the sheet for printing, means for elevating and maintaining said front guide means above said bed before and during the printing operation and for lowering the front guide means below said bed after completion of printing to allow the sheet to slide out of the press along said angularly disposed bed, means for elevating said side guide means above said bed prior to printing and for lowering and maintaining the side guide means below said bed during and after printing, and cam means operable in timed relation with the movement of said squeegee for flexing said screen progressively away from said bed behind said squeegee during printing.

4. In a silk screen printing press having universal application for printing on all types of materials, the combination of a bed for receiving a sheet of material, a screen positioned above said bed, means for moving said bed into contact with said screen for printing, a squeegee movable along said screen for forcing ink therethrough, and combined sheet registering and gripping means adjacent the forward end of said bed, including a plurality of arms mounted for rocking movement and terminating adjacent the forward end of said bed, a flange bar extending transversely of said arms and mounted thereon so as to be movable therewith and with respect thereto, means for elevating said arms above said bed and for lowering said arms a predetermined distance before the printing operation begins, means for moving and holding said flange bar toward said bed in overlapping relation with

the edge thereof to grip the sheet during printing, and means to withdraw said flange bar from said bed after completion of the printing, whereby said flange bar and arms will move below said bed to permit removal of the sheet therefrom.

5. In a silk screen printing press having universal application for printing on all types of materials, the combination of a bed for receiving a sheet of material, a screen positioned above said bed, means for moving said bed into contact with said screen for printing, a squeegee movable along said screen for forcing ink therethrough, and combined sheet registering and gripping means including a plurality of arms mounted for rocking movement and terminating adjacent the forward end of said bed, a flange bar extending transversely of said arms and mounted thereon so as to be movable therewith and with respect thereto, means for elevating said arms above said bed and lowering said arms a predetermined distance before the printing operation begins, means for moving and holding said flange bar toward said bed in overlapping relation with the edge thereof to grip the sheet during printing, means to withdraw said flange bar from said bed after completion of the printing, whereby said flange bar and arms will move below said bed to permit removal of the sheet therefrom, and means to render said flange bar inoperative for gripping when sheet material of a different type is used.

6. A silk screen printing press comprising a main frame, an inclined bed mounted for rocking movement on said frame and adapted to receive a sheet of material to be printed upon, a screen positioned above said bed, cam means for rocking said bed into contact with said screen during printing, a squeegee movable over said screen and in contact therewith for forcing ink through said screen, and cam means operable against the underside of said screen adjacent one end thereof and in timed relation with said first cam means and with movement of said squeegee during printing for flexing said screen progressively away from said bed behind said squeegee.

7. A silk screen printing press comprising a main frame, an inclined bed mounted for rocking movement on said frame and adapted to receive a sheet of material to be printed upon, a screen positioned above said bed, cam means for rocking said bed into contact with said screen during printing, a squeegee movable over said screen and in contact therewith for forcing ink through said screen, guide means for registering the sheet prior to printing thereon, a second cam means for moving said guide means into and out of registering positions, and a third cam means operable in timed relation with movement of said squeegee during printing for flexing said screen progressively away from said bed behind said squeegee.

8. A silk screen printing press comprising a main frame, an inclined bed mounted for rocking movement on said frame and adapted to receive a sheet of material to be printed upon, a screen positioned above said bed, cam means for rocking said bed into contact with said screen during printing, a squeegee movable over said screen and in contact therewith for forcing ink through said screen, guide means including guide fingers for registering the sheet prior to printing thereon and a clamp for, and a second cam means for moving said guide fingers to registering position above said bed prior to printing, for moving said clamp bar into gripping contact on said bed, and for moving said guide means out of register-

15

ing and clamping position below said bed after completion of the printing operation, whereby the printed sheet will be permitted to slide from the bed due to the inclination thereof.

9. A silk screen printing press comprising a main frame, an inclined bed mounted for rocking movement on said frame and adapted to receive a sheet of material to be printed upon, a screen positioned above said bed, cam means for rocking said bed into contact with said screen during printing, a squeegee movable over said screen and in contact therewith for forcing ink through said screen, guide means for registering the sheet prior to printing thereon, a second cam means for moving said guide means to registering position above said bed prior to printing and for moving said guide means out of registering position below said bed after completion of the printing operation, whereby the printed sheet will be permitted to slide from the bed due to the in-

clination thereof, and a third cam means operable in timed relation with movement of said squeegee during printing for flexing said screen progressively away from said bed behind said squeegee, said second and third cam means being mounted on a single cam shaft and arranged to operate in timed relation with each other and with said first cam means.

16

clination thereof, and a third cam means operable in timed relation with movement of said squeegee during printing for flexing said screen progressively away from said bed behind said squeegee, said second and third cam means being mounted on a single cam shaft and arranged to operate in timed relation with each other and with said first cam means.
